No. 690,231.

Patented Dec. 31, 1901.

J. CAMPBELL.

HOOF PAD.

(Application filed Oct. 17, 1901.)

(No Model.)

UNITED STATES PATENT OFFICE.

JOHN CAMPBELL, OF NEW YORK, N. Y.

HOOF-PAD.

SPECIFICATION forming part of Letters Patent No. 690,231, dated December 31, 1901.

Application filed October 17, 1901. Serial No. 78,956. (No model.)

To all whom it may concern:

Be it known that I, JOHN CAMPBELL, a subject of the King of Great Britain, and a resident of the city of New York, borough of 5 Manhattan, in the county and State of New York, have invented a new and Improved Hoof-Pad, of which the following is a full, clear, and exact description.

This invention relates to a hoof-pad which 10 is especially adapted for use by horses having corns or navicular trouble. These corns in most instances form around the frog of the hoof as contradistinguished from on it, and the present invention relates to a form of pad 15 which will relieve a hoof afflicted in the manner mentioned by placing the weight and concussion on the heel and frog of the hoof.

This specification is a specific description of one form of the invention, while the claims 20 are definitions of the actual scope thereof.

Reference is to be had to the accompanying drawings, forming a part of this specification, in which similar characters of reference indicate corresponding parts in all the views.

25 Figure 1 is a bottom view of a pad embodying my invention. Fig. 2 is a section on the line 2 2 of Fig. 1. Figs. 3 and 4 are sections on the lines 3 3 and 4 4, respectively, of Fig. 1; and Fig. 5 is a top view of a pad with the 30 backing removed.

a indicates the backing, which is preferably in the form of a leather sheet, on the under side of which the shoe (not shown) is fastened by devices passing through the backing into the hoof. The pad b lies within the shoe and in the instance shown entirely covers the area inside thereof. The outer edges of the pad conform to the inner margin of the shoe, and the pad has recesses b' at the sides, 35 in which are received the heels of the shoe. These recesses are located forward of the heel at the quarters of the hoof, and the pad is therefore adapted for use in connection with shoes which extend only to the quarter.

40 The pad is fastened by cement or stitching or by any other means desired to the backing a, and the top of the pad is formed with a cavity c, forming an air-chamber. This cavity is of such form that it extends around the 45 frog of the hoof, the two side portions communicating at the front at c'. There is thus provided in the center of the pad a solid bear-

5 ing part d, on a plane with the outer surface d', on which latter the wall of the hoof is afforded a bearing. The central bearing-surface d is located directly under the frog, so as to receive thereon part of the weight of the horse, and extends forwardly to a point beyond the quarter. The passages c' lead from the sides of the cavity c to the heel of 60 the pad and open into the atmosphere, thus permitting the free circulation of air into the cavity, which keeps the air therein cool and prevents the hoof from becoming heated. Now it will be seen that with a pad of this 65 construction the weight and pressure are sustained by the frog-bearing d and the surface d' outside the air-chamber, while the said chamber permits the leather backing to yield if borne upon by a corn on the hoof at the 70 sides of the frog.

Having thus described my invention, I claim as new and desire to secure by Letters Patent—

1. A hoof-pad, comprising a backing of 75 leather, and a facing formed of yielding material and having a cavity in its upper face, said cavity extending along the sides and front of the frog of the hoof, the pad having a solid part located centrally and running 80 from the solid heel part of the pad forwardly beyond the quarter, said central solid part of the pad lying under the frog of the hoof to form a bearing therefor.

2. A hoof-pad, comprising a backing of 85 leather and a facing formed of yielding material and having a cavity in its upper face, the cavity extending along the sides and front of the frog of the hoof, and the pad having a solid part located centrally and running from 90 the solid heel part of the pad forwardly, the central solid part of the pad lying under the frog of the hoof to form a bearing therefor, and the pad also having passages therein leading from the rear ends of the sides of the 95 cavity to the heel of the pad and opening into the atmosphere, for the purpose specified.

In testimony whereof I have signed my name to this specification in the presence of two subscribing witnesses.

JOHN CAMPBELL.

Witnesses:

W. IRVING TAYLOR,

WILLIAM E. PARREMORE.
